TIGHT-LOCK COUPLER AND CONTROL SYSTEM

Herbert E. Van Dorn, Chicago, Ill., assignor to
The Dornvan Corporation, a corporation of
Illinois

Application January 12, 1938, Serial No. 184,548

7 Claims. (Cl. 213—77)

In so-called tight-lock car couplers a tight or rigid interlocking of meeting couplers has heretofore been brought about through the engagement of locking faces somewhat eccentric to each other; the eccentricity producing a wedging action between the locking faces. A disadvantage of this arrangement is that the actual line or narrow band of contact between the locking faces shifts along these faces as wear occurs and may thus 5 endanger the effectiveness of the lock.

One of the objects of the present invention is to produce an improved tight-lock coupler that requires no eccentric or cam-shaped locking surface.

In carrying out my invention, I employ a movable locking block or dog which always occupies the same angular position while performing its locking function, slack being taken up and compensation made for wear by shifting the lock at 10 right angles to the cooperating locking surface. This same type of movement of the lock takes place in locking and in unlocking; the lock being forced against the cooperating locking surface after having been brought into the angular position 15 that is its locking position, and being backed away from that surface before shifting it angularly in unlocking.

The radial or lengthwise shifting movements of the lock are obtained through journaling the lock in eccentric bearing blocks and providing means for shifting these bearing blocks independently of the swinging movements of the lock. In other words, the lock may swing freely between its locking position and its release position without ever coming in contact with the cooperating locking surface; and, when in its locking position, may be shifted bodily from and toward said surface while its angular position remains the same.

Therefore, viewed in one of its aspects, the present invention may be said to have for an object to produce a novel tight-lock coupler in which the lock has angular and rectilinear movements that are entirely independent of each other, which always has the same angular locking position, and which always moves rectilinearly to a given point at the beginning of an unlocking operation and to a variable point, depending upon the condition of both couplers, in completing a 50 locking operation.

A further object of the present invention is to produce a simple and novel mechanism for insuring the proper sequence of lock movements in coupling and uncoupling and the maintenance of the proper conditions for automatic coupling.

It is common practice, in electrically-operated railways, to provide suitable control systems for uncoupling the cars and their air and electric train lines, opening and closing valves in the air lines, and opening and closing switches in the electric circuits, an example of such equipment and control system therefor being disclosed in my prior Patent No. 1,924,821.

Viewed in another of its aspects, the present invention may be said to have for its object an improved control system of this latter type.

The various features of novelty whereby my invention is characterized will hereinafter be pointed out with particularity in the claims; but, for a full understanding of my invention and of its objects and advantages, reference may be had to the following detailed description taken in connection with the accompanying drawings, wherein:

Figure 1 is a side view of my improved car coupler having any usual or suitable electric coupler hung from the same; Fig. 2 is a side view of the car coupler, showing the opposite side of the coupler from that appearing in Fig. 1; Fig. 3 is an elevational view of the locking dog of the car coupler and the eccentric bearing device therefor, detached from the coupler; Fig. 4 is a horizontal section through the car coupler and a fragment of a companion coupler, the locking dog standing a little apart from the member of the companion coupler which it must engage to produce a tight lock; Fig. 5 is a view similar to Fig. 4, showing the coupler in the unlocked condition; Fig. 6 is a section of the irregular broken line 6—6 of Fig. 4; Fig. 7 is a longitudinal section through the operating cylinder for moving the locking dog of the coupler angularly; Fig. 8 is a section through the main, manually operable, controlling valve; Fig. 8a is a section on line 8a—8a of Fig. 8; Fig. 9 is a section through the terminal device of the coupler for automatically coupling together the reservoir lines and brake lines of meeting cars; Fig. 10 is a longitudinal section through an automatic valve device controlling admission of air to the operating cylinder for the locking dog; Fig. 11 is a longitudinal section through an automatic valve device for controlling the admission of air to and exhaust of air from the operating cylinder of mechanism adapted to shift the coupler locking dog radially; and Fig. 12 is a diagram illustrating the entire pneumatic control system.

The car coupler illustrated is of the type having a head that couples with a companion coupler head by moving longitudinally with respect

thereto until physical contact is made, after which the two couplers receive a relative lateral movement on an angle of about forty-five degrees to the longitudinal axis. The coupler head 1, illustrated is, of course, hollow and has on one side of the longitudinal center a forwardly projecting nose 2 that enters the central recess 3 in the front end of a companion coupler, as shown in Fig. 4, in the act of coupling. There is a locking dog 4 mounted in the head behind the recess and adapted to swing into the recess into engagement with the side face 5 of the nose 2 on a companion coupler; the face 5 being parallel with the longitudinal axis of the coupler. The locking dog may be a solid steel casting through one end of which extends a vertical pin 7. The ends of the pin are journaled eccentrically in cylindrical bearing blocks 8 and 9 which are seated and turn in cylindrical bearing seats in the upper and lower walls 20 of the coupler head, as best shown in Fig. 6. The bearing blocks are fixed to or form parts of a U-shaped casting 10, projecting outwardly in opposite directions from the arms of the U adjacent to the free ends of the latter. By moving the casting 10 angularly, the journal pin for the locking dog of the coupler is caused to be shifted bodily from and toward the longitudinal center line of the coupler. Thus, for example, when the locking dog stands at about right angles to the longitudinal axis of the coupler, as shown in Fig. 4, it may be shifted from the dotted line position in which the end is pressed against the face 5 on an opposing coupler, to the position shown in full lines, wherein the end of the locking dog stands clear of the nose of the opposing coupler. The parts are so proportioned that the maximum distance through which the locking dog may be shifted radially by the eccentrics is considerably greater than the gap existing between the locking dog in Fig. 4 and the nose of the opposing coupler, so that by imposing on the eccentrics a force tending constantly to turn them in the direction to cause the locking dog to travel toward the center of the coupler, the locking dog may always be kept tightly pressed against the nose of the opposing coupler, not only when the coupler is new, but after wear has taken place.

In uncoupling, the eccentrics are first turned so as to shift the locking dog from the dotted line position in Fig. 4 to the full line position, after which the dog may be swung rearwardly out of the recess 3. On the other hand, if means are provided to draw the locking dog radially out of its locking position, when free to do so, the locking dog will always be ready to be pushed back by the nose of an oncoming coupler in the act of automatic coupling and then to swing freely into the full line position of Fig. 4.

I have accordingly provided a spring device which normally holds the locking dog retracted in the radial direction, together with means for automatically turning the eccentrics in opposition to the spring and holding the locking dog tightly against the nose of the opposing coupler until it is desired to uncouple. In the arrangement shown, there is a long cylindrical casing composed of two sections 11 and 12 that are telescoped upon each other. Within this casing is a long compression spring 14. The outer end of the section 11, which is closed, abuts against a wall of the hollow coupler head at the rear, while an extension 15 from the front end of the casing section 12 is pinned, as indicated at 16, to a radial projection 17 from the yoke portion of the

U-shaped casting 10. The forward section 12 of the casing is connected by a hinge pin 18 to the free end of one arm of a bellcrank lever 19 mounted to turn upon a fixed vertical shaft or bolt 20 extending through the coupler head from top to bottom. When free to do so, the spring 14 expands the telescopic casing and thus turns the member 10 into and holds it in the position illustrated in Fig. 4. When the bellcrank lever is turned about the shaft 20 in the counter-clockwise direction, as viewed in Fig. 4, the forward section 12 of the telescopic casing is drawn back, compressing the spring 14 and turning the eccentric bearing blocks in the direction to shift the locking dog of the coupler bodily toward the central axis of the coupler.

The locking dog 4 is acted upon by a spring that tends constantly to swing it into and hold it in a forward angular position, and by a suitable pneumatic power device serves to swing 20 the locking dog rearwardly and out of the recess 3. In the arrangement shown, there is a long L-shaped arm 21 fixed at the free end of its arm to the back of the locking dog near the free end of the latter, the long element of this 25 arm extending more or less parallel to the locking dog out through the side of the coupler head where it is connected to the power device. The details of this power device are best shown in Fig. 7, the same comprising a cylinder 22 containing a piston 23 and a telescopic piston rod comprising a tubular outer section 24 that extends from the exterior of the cylinder through one end of the latter and into engagement with one side of the piston. The other section 25 of 35 the piston rod, is a short cylindrical member fixed to the piston and slideable in the tubular section. On the inner end of the piston rod member 24 is secured an annular external flange 26 between which and the cylinder head through 40 which the cylindrical rod passes is located a compression spring 27. To the outer end of the piston rod member 24 is fixed a part containing an eye 28 that is elongated crosswise of the axis of the rod. A pin 29, fixed in the free outer 45 end of the arm 21, extends through this elongated eye, thereby providing a connection between the piston rod and the arm 21 that permits the piston rod to move back and forth in a straight line while the arm 21 has swinging 50 movements, without binding. It will be seen that when two couplers come together, each pushes back the locking dog of the other to about the position illustrated in Fig. 5. This is done against the resistance of the spring 27; this spring 55 being compressed as the tubular outer member of the piston rod is drawn forward by reason of its connection with the locking dog. During this time the piston 23 remains stationary so as not to interfere with the return of the dog to its 60 locking position after the nose 2 on the companion coupler moves in far enough to clear the same, as indicated in Fig. 4. In uncoupling, with the locking dog in the position shown in Fig. 4, when air under pressure is admitted behind the piston in the cylinder 22, the piston and both of the piston rod sections are forced forward against the resistance of the spring 27 and thus bring the locking dog and the piston rod into the positions illustrated in Fig. 5.

As previously stated, the spring 14 normally, or when the coupler is idle, holds the eccentrics in what may be termed their release positions, namely the positions that prevent the locking dog from pressing against the nose of an opposite 75

coupler properly nested with the coupler in which the locking dog is mounted. Assuming that the locking dog is standing in the position indicated in full lines in Fig. 4 at the time two couplers 5 are brought together, and that the dog is pushed back by the nose of the oncoming coupler into the position shown in Fig. 5, and is then returned, through the action of the spring 27, to the full line position of Fig. 4, it is necessary that 10 the dog be shifted radially into forcible contact with the nose of the opposing coupler, in order to complete an automatic coupling operation. I have therefore provided means for operating the 15 eccentric bearing blocks automatically after the two couplers have come together. In the arrangement shown, the coupler head is provided with means for automatically connecting together the reservoir lines and the brake lines of two meeting cars. The terminal for the reservoir 20 line, in the coupler head, is indicated at 30 in Figs. 4 and 5. Air is supplied from the terminal 30, upon completion of the connection between the air lines, to turn the eccentric bearing blocks. The details of the two terminals, that for the 25 brake line being indicated at 31, are best shown in Fig. 9. Referring to this figure, it will be seen that the terminal 30 has in the outermost portion a cylindrical bore 32 in which is slidably arranged a hollow plunger 33 that constitutes a 30 stem for a valve 34 arranged in the body portion of the terminal and cooperating with a bearing seat at the inner end of the bore 32 to shut off communication between the local reservoir line and the bore 32 when the valve is closed. The 35 member 33 is hollow in the sense that it is in the form of a tube closed at the valve end. A section of the cylindrical stem adjacent to the valve is of reduced diameter, as indicated at 35, and is provided with an opening or port 36 leading 40 into the interior of the stem. The terminal member has in communication with the annular space surrounding the reduced section 35 of the valve 45 stem a screw threaded opening 37 for the attachment of a tube or pipe. Behind the valve 34 is a spring 38 which normally holds it closed. The forward end of the hollow valve stem projects beyond a rubber gasket 39 in the front face of the terminal. In the normal condition of the parts, with the coupler idle, the pipe that is 50 connected to the screw threaded opening 37 is vented to atmosphere through the hole or port 36 and the interior of the hollow valve stem. When two cars come together, the valve stems on their meeting 55 couplers engage each other and act mutually to open the two valves. This shuts off communication between the pipe connected to the screw-threaded hole 37 and atmosphere and places this pipe in communication with the interior of the reservoir train line on both cars. Therefore, if 60 there be air under pressure in the reservoir line of either car, such air can flow out into the pipe connected to the screw-threaded hole 37. This pipe is indicated at 40 in Figs. 4 and 5 of the drawings, where it is also illustrated as containing a valve 41. The valve 41 is opened and closed 65 through the operation of a handle 42. The free end of the handle is pinned to one end of a link 44 whose other end is journaled on the vertical post or shaft 28. A second link 45 extends between a point at about the middle of the member 44 and the elbow of the L-shaped arm 21 fixed to the locking dog of the coupler, being pinned to each, as indicated at 46 and 47, respectively. Therefore, when the locking dog swings, it opens 70 and shuts the valve 41; the valve being open

when the dog is in or near its locking position, as illustrated in Fig. 4, and being closed at other times.

The pipe 40 supplies air to an actuator for the bellcrank lever 19 so that, upon the coming together of two couplers, communication between this pipe and atmosphere is shut off and the pipe is opened at the valve 41 so as to permit air from the reservoir line to flow into and through the same to such actuator. 5

The actuator for the bell crank lever 19, as best shown in Figs. 4 and 5, comprises a cylinder 48 having therein a piston 49 provided with a piston rod 50 that extends out through the front end of the cylinder. On the front end of the piston rod 50 is an elongated eye 51 through which passes a pin 52 fixed in the second arm of the bellcrank lever 19, between the ends of the latter. When air is admitted into the rear end of the cylinder 48, the piston is pushed forward and 20 the bellcrank lever is rocked in the counter-clockwise direction, drawing the member 12 of the telescopic spring casing, that is connected to the eccentric bearing device, rearwardly in a diagonal direction and turning the eccentrics so as 25 to shift the locking dog 4 from the full line position of Fig. 4 to the dotted line position.

Air does not flow directly from the pipe 40 into the cylinder 48, but it first passes through the casing 53 of a controlling device and leaves this 30 casing through a pipe 54 which is connected to the rear end of the cylinder 48. The controlling device just mentioned serves also to exhaust the cylinder 48 and to supply air for actuating the piston in the cylinder 22 of the actuator for 35 swinging the locking dog. At any rate, as long as there is air in the reservoir line and the cars are coupled, the controlling device just mentioned permits pressure to be maintained in the cylinder 48 and thus insure that the locking dog will have 40 a constant pressure exerted on the same in the radial direction to force it into intimate contact with the nose of the opposing coupler.

The locking dog must be brought into the full line position of Fig. 4 before the cylinder 22 is 45 energized to swing the dog back into the head in order to uncouple. While there is air pressure in the rear end of the cylinder 48, however, this is impossible because the bellcrank lever 19 is then holding the eccentrics in the positions which 50 cause the locking dog to occupy the dotted line position of Fig. 4.

Therefore, the rear end of cylinder 48 must be exhausted and air under pressure be admitted into the front end to return the parts to the positions illustrated in Fig. 4 before air is admitted to cylinder 22. Air for pushing the piston in cylinder 48 toward the rear is supplied through a branch 55 from a pipe 56, shown in Fig. 5. A second branch pipe 57 enters one end of a valve 60 casing 58. A valve stem 59 projects out through the opposite end of the casing 58 in the plane of the arm of the bellcrank lever that is connected to the piston rod 50; whereby the stem is pushed rearwardly into the casing 58 when the piston in cylinder 48 is forced rearwardly. As shown in Fig. 10, the stem 59 carries at its inner end a valve 60 which controls communication between the two chambers in the casing 58. The pipe 57 is secured to the casing so as 65 to be in communication with one of said chambers while a pipe 61 is connected to the other chamber. The pipe 61 leads to the rear end of cylinder 22. Consequently, when there is air in pipe 55 and the piston in cylinder 48 is in its 70 75

retracted position, air can enter the rear end of the unlocking cylinder 22 and thus cause the lock 4 to be swung back into its full release position, as indicated in Fig. 5.

As will hereinafter appear, the pipe 56 serves to vent the instrumentalities which it supplies with air under pressure, but other means must be provided to vent the rear end of cylinder 48 whenever air under pressure is introduced into the front end. That is one purpose of the devices housed in the casing 53 heretofore mentioned. As shown in Fig. 11, the interior of the casing is divided into three chambers, A, B and C, separated from each other by partitions 63 and 64. The chamber A has an inlet 65 to which the pipe 40 is connected and the chamber B has an opening 66 from which the pipe 54 leads. Each partition has a central hole therethrough, as indicated at 67 and 68. In the chamber A is a piston 69 having a small passage 69a extending through the same and provided with a stem 70 smaller in diameter than the opening 67, reaching through this opening into chamber B. In chamber B is a cup-shaped member 71 into which the free end of the stem 70 extends. A spring 72, behind the piston 69, normally forces the piston toward the partition 63 and causes the stem 70 to press the member 71 against the partition 64. Thus, normally, air may flow freely through this device from pipe 40 to pipe 54 and thence to the rear end of the cylinder 48, the part 71 serving as a valve to prevent air from passing over into chamber C. In the chamber C is a piston 74 provided with a long stem 73 extending therefrom through opening 68 and into engagement with the member 71. Partition 64 is hollowed out and there is a port 75 leading from atmosphere to the cavity 76 in the partition; this cavity communicating with the opening 68. In the outer end of chamber C is a screw-threaded opening 77 to which, as shown in Fig. 5, a branch 78 of pipe 56 is connected.

It will be seen that upon admitting air under pressure behind the piston 74, then, because of the size thereof, it travels toward the right as viewed in Fig. 11 until the member 71 engages the partition 63 and shuts off communication between chambers A and B and opens communication between chamber B and atmosphere. As a result, the rear end of cylinder 48 exhausts through pipe 54, said chamber B, and exhaust port 75. Since this occurs at the same time that air is admitted into the front end of the cylinder 48, the piston in that cylinder may travel freely toward the rear under the pressure in front thereof.

The terminal or coupling unit for the reservoir and brake lines is of rather unique construction. The body of this unit comprises a single coating 60 extending diagonally through the coupler head inwardly from the nose 2 and secured to the head by two ears 80 located about midway between the ends thereof and engaged with a vertical rib-like part 81 on the coupler head; bolts 82 extending through the ears and the part 81. The complete unit can therefore be manufactured as such and be easily applied and removed for repairs or other purposes.

It is sometimes desirable to be able to operate the locking dog manually. To permit this, the dog 4 may be provided with a set screw 84 by which it may be secured to the pin or journal 7; and the pin or journal projects up above the top of the coupler head and is there provided

with a non-circular portion 85 adapted to receive a wrench.

It is not enough to control the coupler, because the air lines must also be opened and closed and the electric train circuits be made and interrupted in proper relation to each other and to the coupling and uncoupling of cars. I have therefore created a system of control that is simple and is easy to operate, safe, efficient and reliable under the varying service conditions encountered. The control system required at each end of a car is illustrated diagrammatically in Fig. 12 which includes, in addition to the parts heretofore specifically described, what is known as an air cut out base and a cut out switch.

The air cut out base includes two valves 86 and 87 in the reservoir and brake pipes 88 and 89, respectively. The two valves are connected together by a shaft 90 having a wide radial vane 91 extending lengthwise thereof. On opposite sides of the shaft are pneumatic cylinders 93 and 94 having piston rods 95 and 96, respectively, projecting therefrom toward said vane. When air enters the lefthand cylinder, the piston therein is driven toward the right and the piston rod engages the vane and rocks the valve-operating shaft to close both valves; whereas, under similar conditions, the piston rod 96 forces the vane into the position illustrated in the diagram and opens both valves.

In order that there may always be air available to perform the automatic coupling operations if the reservoir line in either of two meeting cars contains air under pressure, I provide a by-pass around the valve 86 in the reservoir line. This by-pass may take the form of a small pipe 97 having a valve 98 therein. When the valve 86 is closed, a small amount of air can flow through the by-pass and insure the presence of enough air in the pipes 40 connected to the two meeting couplers, to energize the cylinders 48 on both of them and supply air to open the main air valves and close the main or cut out switch.

The cut out switch may be of any suitable type, the diagram indicating a switch 99 having four drums the ends of whose shafts are visible at 100, 101, 102 and 103. Two of the drums are operated by a pneumatic power device containing a cylinder 104, and the other two are driven by a similar device having a cylinder 105. The drums are intended to be turned in one direction by springs, not shown, so that each power device need be only single acting. The corresponding pressure-receiving ends of the cylinders are connected by a pipe 106 having therein a hand valve 107 through which one of the cylinders may be vented to atmosphere, if desired.

The uncoupling of the cars, the opening and closing of the main air valves, and the opening and closing of the switch are all controlled from a master controller 110, which may be identical with the master valve in my aforesaid Patent No. 1,924,821, with the addition of a separate valve for admitting air to the cylinder 94 for closing the main valves in the reservoir and brake lines. The details of this master controller are illustrated in Fig. 8. It will be seen from Fig. 12, that an air pipe 111 leads to an extension 112 of the casing of the controller 110. This extension constitutes an air chamber extending past three plug valves 114, 115, and 116, as shown in Fig. 8. The valve 114 admits air from the chamber 112 to a chamber 117, a wall of which has a screw-threaded opening 118 to receive the pipe 56 of Fig. 12. The valve 115 admits air from chamber 75

112 to a chamber 120, one of the bonding walls of which has a screw-threaded opening 121 that receives the pipe 122 of Fig. 12. This portion of the controller is exactly like that of my aforesaid patent, including the handle 123 for the plug 115, the detachable handle 124 for the plug 114, and the interlock 125 between these two plugs. The valve 116 admits air from chamber 112 into a chamber 126 having in a wall thereof a screw-threaded opening 127 to receive the pipe 128 of Fig. 12. The valve 116 is independent of the other two, 114 and 115, except that it is provided with a stem 129 adapted to be engaged by the same handle 124 that operates the valve 114. Consequently, the valve 116 can be operated only at a time when the valve 114 is in such a position that the handle 124 can be detached therefrom.

Referring now to the diagram, it will be seen that a branch 130 from the pipe 40 leads up through a valve 131 to the pipe 111. Thus, air can flow from the pipe 40 into the main chamber or manifold 112 of the master controller, or air can be taken from the main reservoir line through a pipe 132 leading from the reservoir line to the valve 131. The pipe 56 connected to the master controller continues to the corresponding end of the car where it has a terminal 134 adapted to cooperate with a companion terminal of a meeting car; the terminal 134 being conveniently arranged in an electric coupler, such as shown at 135 in Fig. 1, as is customary. There are four branch pipes leading from the pipe 56, including the pipes 55, 57 and 58, together with a pipe 136 which leads to the air cut out cylinder 93. Thus, with the valve 114 in one position, air enters the cylinder 93 to close the main valves; air also enters the front end of the cylinder 48 to force the piston rearwardly; air enters the lower end of the controlling device 53, and thus exhausts the rear end of cylinder 48 to atmosphere; and, when the piston of the cylinder 48 reaches the rear limit of its movement, so that the valve in the device 53 is opened, air flows through this device, from the pipe 57 and into the pipe 61 to the uncoupling cylinder. Because of the interlock between the valves 114, 115, air cannot be admitted to the pipe 56 until the supply of air to the switch cylinders 104 and 105 has been cut off and the cut out switch has been opened. In other words, the cars cannot be uncoupled until the electrical circuits have been interrupted. After cars have been coupled together, air can be admitted through the pipe 128 to the piston 94 of the air cut out, so as to open the valves in the reservoir and brake lines; but this can be done only after the valve 114 has been turned into the position to permit the removal of the handle 124.

In Fig. 3 the valves are shown in the positions which they occupy before a car is coupled to another car, the chambers 117 and 126 being vented to atmosphere and the chamber 120 being connected to chamber 112. Notwithstanding that the switch cylinders are now connected to chamber 112, they, likewise, contain only air at atmospheric pressure, because the pipe 40 from which the chamber 112 receives its supply of air under pressure, is vented through the normally open valve 41 and the valve stem 33 in the reservoir terminal 30. Pipe 56 being opened to atmosphere through valve 114, the valve-closing cylinder 93 of the air cut out base is exhausted as is the front end of the cylinder 48. Fig. 8a illustrates the port and passage arrangement

with respect to one of the valves, all of which are alike. It will be seen that the valve casing has adjacent to each valve an exhaust port 137, a port 138 leading to the chamber to be supplied with air by that valve, and a port 139 leading into the chamber 112. Each valve contains a passage 140 which, in one working position of the valve, connects ports 138 and 137 and in its other position connects ports 138 and 139.

As in my aforesaid patent, the handle 124 can be removed only when the valve 114 is in the exhaust position and this may also be true with respect to the valve 116; so that air under pressure cannot be admitted to both air cut out cylinders 93 and 94 at the same time. Of course, the interlock 125 prevents the valve 114 from being moved into its energizing position until the valve 115 has been turned to exhaust, thereby preventing uncoupling before the switch has been opened.

With the valves of the master controller in the positions indicated in Fig. 3, the bringing of the car coupler and a companion coupler together causes the couplers to be locked in tight engagement with each other and the main switch to be closed. Then the valve 116 may be turned by means of the handle 124 to energize the cylinder 94 and open the main valves in the reservoir and the brake pipes. The pipe 128 is connected to a terminal 141 adjacent to the terminal 134, by a pipe 142, so that the operation of the valve 116 on either car will open the main air valves on both of two connected cars.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

1. In combination, a car coupler having a movable lock, a pneumatic actuator for moving the lock into its unlocking position, means for relieving the pressure between the lock and the part of a companion coupler to which the said car coupler is coupled, a pneumatic actuator for said means, and means to energize both actuators and delay the energization of the first mentioned actuator until after the said pressure has been relieved.

2. In combination, a car coupler having a lock movable angularly into locking and unlocking positions and radially to prevent contact between the lock and the part on a companion coupler with which it cooperates when a coupling is made, means automatically to swing said lock into locking position upon coupling, a pneumatic actuator for moving said lock radially into contact with the cooperating part on the companion coupler, and means controlled by the lock to energize said actuator.

3. In combination, a car coupler having a lock movable back and forth in two directions transverse to each other in locking and unlocking, a pneumatic actuator to effect the back and forth movements of the lock in one direction, a spring and a second pneumatic actuator acting in opposition to each other to bring about the other movements of the lock, means to energize the first and then the second pneumatic actuator in uncoupling and means to energize the first actuator in the act of coupling only after the lock nears the ultimate position into which the spring tends to move it.

4. In combination, a car coupler having a lock movable angularly between locking and unlock-
5 positions and also radially, a reversible pneu-
matic actuator for moving the lock radially, a
spring to move the lock angularly into locking
10 position, a pneumatic actuator to move the lock
angularly into unlocking position, means to ad-
mit air to the first actuator when the lock nears
15 its locking position to cause the lock to be forced
tightly against the cooperating member in a
companion coupler in making a coupling, and
means to admit air to the first actuator to cause
the lock to be backed away from the said mem-
ber and air to be thereupon admitted to the
15 second actuator in uncoupling.

5. In combination, a car coupler including a
lock spring-held in a locking position and
adapted to be pushed out of the way by an ele-
ment of an oncoming coupler and then move
20 into locking relation to the latter, a pneumatic
actuator which it is desired to keep deenergized
except when the coupler is coupled to a com-
panion coupler, a train pipe, a conduit for sup-
plying air to said actuator, means operable by
25 the coupling of said coupler to another coupler
to open communication between said train pipe
and said conduit, a shut-off valve in said con-
duit, and a connection between the latter valve
and the lock to cause the valve to remain closed

except when the lock is in or near its locking
position.

6. In an automatic car coupler, a coupler head,
a lock in the head, a pin on which the lock is
5 mounted for swinging movements relative to
the coupler, rotatable bearing blocks in which
the pin is eccentrically mounted, a pneumatic
actuator, a connection between said actuator and
the bearing blocks to turn the latter back and
10 forth, a spring tending constantly to hold the
lock in its locking position, and a second pneu-
matic actuator to move said lock into its release
position.

7. In an automatic air coupler, a coupler head,
a lock in the head, a pin on which the lock is
15 mounted and to which it is fixed for swinging
movements relative to the coupler, rotatable
bearing blocks in which the pin is eccentrically
mounted, a pneumatic actuator, a connection be-
tween said actuator and the bearing blocks to
20 turn the latter back and forth, a spring tending
constantly to hold the lock in its locking posi-
tion, and a second pneumatic actuator to move
said lock into its release position, the connection
25 between the lock and said second actuator being
such that the lock may be swung back and forth
while that actuator remains stationary.

HERBERT E. VAN DORN.
